F. GAISLER,
CORE FORMING APPLIANCE FOR PATTERNS.
APPLICATION FILED SEPT. 10, 1917.

1,296,945.

Patented Mar. 11, 1919.

UNITED STATES PATENT OFFICE.

FRED GAISLER, OF ST. LOUIS, MISSOURI, ASSIGNOR OF ONE-HALF TO FRED GRAF, JR., OF ST. LOUIS, MISSOURI.

CORE-FORMING APPLIANCE FOR PATTERNS.

1,296,945.

Specification of Letters Patent. Patented Mar. 11, 1919.

Application filed September 10, 1917. Serial No. 190,486.

To all whom it may concern:

Be it known that I, FRED GAISLER, a citizen of the United States of America, a resident of the city of St. Louis, in the State of Missouri, have invented certain new and useful Improvements in Core-Forming Appliances for Patterns, of which the following is a full, clear, and exact description, reference being had to the accompanying drawings, forming a part of this specification.

My invention relates to improvements in patterns, and more particularly to means whereby a green sand core can be formed at the time the main part of the mold is formed. The new core-forming device can be used to form a straight core, uniform in diameter throughout its length, such, for example, as a car wheel core. The invention can be used in making various kinds of cores which, owing to the lack of "draft", cannot be formed by the pattern itself. In the manufacture of car wheels it is customary to use dry sand cores, and the labor and expense of making and handling such cores is entirely eliminated by the present invention. Furthermore, the green sand core formed by the new device can be more easily removed from the casting, and since the core is formed as an integral part of the green sand mold, there are no fins or rough corners at the junction of the core and the main body of sand.

The preferred form of the invention comprises a pattern provided with a core-receiving opening, and a core-forming sleeve arranged in said opening to form the core therein. The pattern can be lifted from the core-forming sleeve, leaving the latter in the mold. This sleeve is preferably made of segmental sections, separable from each other, so they can be easily removed from the core after the pattern has been drawn from the mold.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a vertical section of a flask,

showing a pattern provided with a core-forming device constructed in accordance with my invention.

Fig. II is an enlarged fragmentary plan view, partly in section, showing the central portion of the pattern and the core-forming device arranged therein.

Fig. III is a vertical section illustrating the parts shown in Fig. II.

The flask herein shown comprises a drag 1, a bottom board 2, a cope 3 provided with a basin 4 into which the molten metal is poured, and gates 5 through which the metal flows from the basin to the mold. A chill ring 6 is arranged between the cope 7 and the drag.

A designates a pattern, preferably made of wood, the pattern shown being used in making car wheels. A tapered metal sleeve 7 forms a lining for a core receiving opening at the center of the pattern, said sleeve being permanently secured to the wooden pattern. This tapered sleeve is larger in diameter at the bottom than at the top, so that the pattern can be readily lifted from the core-forming device, which will be presently described. 8 designates a sheet metal web closing the top of the core-receiving opening at the center of the pattern. The annular margin of the web 8 is arranged between rings 9 and 10 and secured to the pattern by means of screws 12, which pass through said rings.

B designates a core-forming device preferably consisting of two semi-cylindrical sections 13 abutting against each other at the points indicated by 14 in Fig. II. The internal diameter of the core-forming sleeve may be uniform throughout the entire length of the sleeve, and the sleeve sections 13 may be separated from each other and removed from the core after the pattern has been removed from the mold. Each sleeve section 13 is provided on its outer face with tapered ribs 15, which engage the inner face of the tapered lining 7. The lower edge of each sleeve section 13 is widened, or flanged outwardly, as shown at 16, to engage the relatively large lower margin of the lining 7. The upper edge of each sleeve section 13 is fitted to the sheet metal web 8 at the top of the core-receiving opening, the lower edge being flush with the bottom of the pattern and firmly fitted to the lining 7.

In forming the mold the green sand, rammed into the drag, is forced into the sectional core-forming sleeve B, and also forced onto the sheet metal web 8. The 5 cope is formed in the usual manner by ramming the sand on top of the pattern. The sectional core-forming sleeve is held in position by frictionally engaging the lining 7, and also by engaging the sheet metal 10 web 8. The parts are thus secured together in such a manner that the pattern can be readily lifted from the core-forming sleeve B, and thereafter said sleeve may be easily removed from the core by moving 15 the sleeve sections 13 away from each other. By splitting the sleeve longitudinally to form the two segmental sections 13, and by combining these sections with a pattern as herein shown, a highly desirable core can 20 be made of green sand at a very low cost, thereby entirely eliminating the labor and expense due to the making and handling of dry sand cores. The pattern having the tapered core-receiving opening can be very 25 easily removed from the sectional core-forming sleeve, and the latter can be easily and quickly removed from the core.

I claim:

1. A car wheel pattern provided with a 30 central core-receiving opening, a sheet metal web closing the top of said core-receiving opening, a core-forming sleeve arranged in said opening and extending from said sheet metal web to the bottom of the 35 opening, the internal diameter of said core-forming sleeve being uniform approximately throughout the length of the sleeve and said sleeve being split longitudinally so that it can be readily removed from the core, said 40 core-forming sleeve being removably fitted

to the pattern and the parts being so formed that the pattern can be readily lifted from said sleeve.

2. A car wheel pattern provided with a 45 central core-receiving opening, a sheet metal web secured to said pattern and closing the top of said core-receiving opening, a sectional core-forming sleeve comprising segmental sections arranged in said opening and extending from said sheet metal web 50 to the bottom of the opening, the internal diameter of said sectional core-forming sleeve being uniform throughout approximately the entire length of the sleeve and the sections constituting said sleeve being 55 separable from the pattern and separable from each other so they can be readily removed from the core, the wall of said central core-receiving opening being tapered to allow the pattern to be readily lifted from said sectional core-receiving sleeve, and said sections being widened at their lower margins to engage the relatively large lower margin of said wall.

3. A pattern provided with a core-receiving opening, a closure for the top of said core-receiving opening, said opening being open at the bottom to receive the sand, and a core-forming sleeve arranged in said opening and extending from said closure 70 to the bottom of the opening, said core-forming sleeve being split longitudinally so that it can be readily removed from the core, said core-forming sleeve being removably fitted to the pattern and the parts being 75 so formed that the pattern can be readily lifted from said sleeve.

In testimony that I claim the foregoing I hereunto affix my signature.

FRED GAISLER.
